UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

CLOTH-CUTTING ATTACHMENT FOR LOOMS.

Application filed April 8, 1927. Serial No. 181,995.

This invention relates to an attachment for a loom for cutting or splitting the cloth into a plurality of strips during the weaving operation. Such attachments are useful 5 for many purposes and particularly when the cloth is woven with what is known as an intermediate or center selvage, in which case the attachment cuts through the center of the longitudinal section of weaving forming this intermediate or center selvage.

The object of the invention is to provide an attachment of this character so constructed as to prevent any injury to the loom operative by reason of accidental contact with the cutting instrumentality forming the essential element of the attachment.

The object of the invention further is to provide an attachment of this character which will insure the cloth as it is woven being guided into contact with the cutting edge and stretched taut thereover and thus secure accurate continuous cutting of the cloth.

The object of the invention further is to provide an attachment of this character which will be of simple and strong construction, capable of the necessary adjustments, and readily secured in position on the loom.

These and other objects and features of 30 the invention will appear more fully from the accompanying description and drawings and will be particularly pointed out in the claim.

The attachment is rigidly secured from 35 the loom frame and conveniently by being bolted or riveted to the cloth beam which extends across and above the cloth forwardly of the fell. As many of these attachments may be thus secured as is desired depending 40 upon the number of strips into which the cloth is to be cut as it is woven.

The drawings illustrate so much of a loom as is sufficient for a disclosure of a preferred form of the invention.

45 In the drawings:

Fig. 1 is a view in perspective of a portion of the cloth beam, sand roll and guide roll of a loom showing one attachment embodying a preferred form of the present invention in position and acting to cut a center selvage section.

Fig. 2 is a view in side elevation partially in vertical cross section of the attachment including a portion of its supporting bracket.

Fig. 3 is a view in front elevation of the attachment.

Fig. 4 is a view in cross section taken on the line 4—4 of Fig. 2.

Fig. 5 is a view in cross section taken on the line 5—5 of Fig. 2.

The breast beam 1 is a rigid portion of the loom frame which extends across the loom at the front between the side frames, usually directly over the sand roll 2 and a 65 guide roll 3 around which the cloth 4 as it is woven passes on its way to the take-up and cloth rolls. This breast beam is here illustrated as a convenient support for the cutting attachment. The cloth illustrated 70 is shown as woven with a central longitudinal strip 5 in which some of the warps are omitted and which forms a center selvage or, when severed, a selvage for each of the strips into which the cloth is thus cut. 75 It will be understood, however, that the attachment is useful for cutting the cloth into strips quite independent of any peculiarity in the weave and that as many of these attachments may be employed as will be found 80 desirable.

A supporting bracket 6 is bolted or otherwise secured as indicated at 7 to the breast beam and projects rearward therefrom above the plane of the cloth. A vertical post 8 85 herein shown as cylindrical is mounted in the rearward end of the bracket 6 and is vertically adjustable therein by means of the set screw 9. This post at its lower end is vertically slotted and in this slot is 90 mounted the knife blade 10 held in place by suitable pins or rivets 11.

The knife blade is thus rigidly secured through the post 8, the bracket 6 and the breast beam 1 from the loom frame.

95 The knife blade extends rearward of its shank and presents a cutting member edge 12 which, it will be seen, is inclined forward and upward. This knife blade also stands vertically and parallel with the warps. Its 100 cutting edge 12 crosses the plane of the cloth and its rear end extends well below the plane of the cloth.

A guard presser foot is also rigidly secured from the loom frame by being secured 105 to the post 8. This guard foot comprises a foot portion 13 and a shank 14 terminating at its upper end in a head 15 fitting over the post 8 and adjustable thereon by means of the set screw 16. The foot portion 13 110

extends rearward above the cutting edge 12 of the knife blade and up to the rear end of the knife blade, or, in fact, somewhat beyond the rear end of the knife blade, as shown in Figs. 2 and 4. The rear end of the foot portion 13 flares upward and thus forms with the inclined rear end of the knife blade an open, forwardly converging mouth 17. The guard foot is also curved transversely so as to form at each side of the knife blade and spaced therefrom a depending rigid wing 18. In the construction illustrated, these wings are continued up the shank 14 and fit against the forward end of the bracket 6 to assist in positioning the guard presser foot.

It will thus be seen that the guard presser foot in cooperation with the knife blade performs three important functions. First, it thoroughly and completely guards and protects the cutting edge 12 of the knife blade so that it is impossible for the operative to come in contact with this cutting edge while working about the loom, as in picking out a broken weft or in handling the shuttle. Second, it forms with the knife blade the forward converging mouth 17 which acts to guide the cloth directly on to the cutting edge. Third, the wings 18 act as the cloth moves forward to press the cloth down and thus stretch it taut as it rides against the cutting edge, as shown in Fig. 5, thus to insure the desired cutting action.

The construction is extremely simple and

efficient, may be readily mounted in position and adjusted upon any given loom and acts efficiently to cut the cloth without danger to the operative.

Having thus described the invention, what is claimed as new, and desired to be secured by Letters Patent, is:

An attachment for looms for cutting the cloth longitudinally as it is woven comprising a knife blade adapted to be rigidly secured on a loom frame, having a forward and upward inclined cutting upper edge, the said knife blade standing vertical and parallel with the warps and with the cutting edge crossing, and at its rear end extending below, the plane of the cloth, and a guard presser foot rigidly secured upon the loom frame and extending rearward above, and up to the rear end of, the cutting edge of the knife blade, thus to protect the operative from any accidental engagement with the cutting edge, the rear end of said guard foot flaring upward to form with the knife blade beneath an open, forward converging mouth for guiding the cloth onto the cutting edge, the said guard foot having a depending rigid wing at each side of and spaced from the knife blade forwardly of said mouth, which wings act, as the cloth moves forward, to press the cloth down and thus stretch it taut as it rides against the cutting edge to insure the cloth being cut.

In testimony whereof, I have signed my name to this specification.

HARRY A. DAVIS.
